(57) **CLAIM**

The ornamental design for a container sleeve, as shown and described.

DESCRIPTION

FIG. 1 is a perspective view of the container sleeve showing my new design;

FIG. 2 is a top view of the container sleeve shown in FIG. 1;

FIG. 3 is a front view of the container sleeve shown in FIG. 1;

FIG. 4 is a right side view of container sleeve shown in FIG. 1;

FIG. 5 is a bottom view of the container sleeve shown in FIG. 1;

FIG. 6 is a rear view of the container sleeve shown in FIG. 1; and,

FIG. 7 is a left side view of the container sleeve shown in FIG. 1.

The broken lines in FIGS. 1, 3, 4 and 7 depict portions of the container sleeve or environment that form no part of the claim.
